UNITED STATES PATENT OFFICE.

MCCLINTOCK YOUNG, OF FREDERICK, MARYLAND, ASSIGNOR TO THE
DIAMOND MATCH COMPANY, OF CONNECTICUT.

MACHINE FOR CUTTING AND FILLING MATCH-SPLINTS.

SPECIFICATION forming part of Letters Patent No. 415,934, dated November 26, 1889.

Application filed May 29, 1889. Serial No. 312,541. (No model.)

To all whom it may concern:

Be it known that I, MCCLINTOCK YOUNG, a citizen of the United States, residing in the city and county of Frederick, in the State of Maryland, have invented certain new and useful Improvements in Machines for Cutting and Filling Match-Splints, of which the following is a specification.

My invention relates to a class of machines in which a series of match-splints are simultaneously severed from a strip or veneer of a thickness equal to that of the splints and of a width equal to their length. Each alternate splint is then shoved endwise transversely to the line of feed a sufficient distance to separate the ends of the splints for dipping, thus forming a double-edged comb, which by a further continuance of the endwise movement is inserted between the bars of a frame traversing transversely the line of movement of the comb, so that each comb is in turn inserted between its respective bars of the holder-frame.

The object of the first part of my invention is certainly and effectively to feed the strip to the cutters. These ends I attain by causing the edges of the strip to travel in fixed guides while its opposite faces are acted upon by a feed-roller, and by a pressure-roller capable of yielding to accommodate itself to variations in the thickness of the strip, while always maintaining a bite thereon.

The object of the next part of my invention is to adapt the cutting mechanism to the efficient performance of the work, which end I attain by employing a series of independent cutters adjustably mounted in a common head, which head is in turn adjustable in suitable guides, so as to compensate wear and secure the necessary relation of the cutters to the other parts of the mechanism.

The object of the next part of my invention is to form the splints into a double-toothed comb, which end I attain by holding each alternate splint by means of a friction brake or stop and shoving the intermediate ones endwise a sufficient distance to form the teeth of the comb by a pusher-rake moving in a plane parallel with but transverse to the line of feed.

The object of the next part of my invention

is to fill a frame with match-splints properly arranged for dipping, which end I attain by shoving the comb, formed as set forth in the preceding paragraph, endwise a further distance by the continuance of the movement of the same pusher-rake as that which formed the comb, thus inserting the comb between the yielding bars of a holding-frame transversely traversing the line of feed and that of the motion of the comb, so that a series of the combs are thus inserted in the holder.

The object of the next part of my invention is automatically to traverse the holding-frames across the line of feed of the combs, so as to insure their proper and successful insertion therein, which end I attain by causing the holding-frames to traverse in guides actuated by pawls acting directly on the holding-frame.

The object of the next part of my invention is to provide a splint-holding frame in which the splints will be securely held, and from which they can readily be removed when desired, which end I attain by constructing the splint-holding frame of parallel holding bars or clamps held in proper relation by the side pieces connected therewith by detachable fastenings, so that one of the side pieces may readily be detached to permit of the removal of the splints from their holding-bars by shoving them laterally sidewise.

My invention further consists in certain constructions, combinations, and organizations of the above-mentioned instrumentalities with other mechanism hereinafter described, the subject-matter of which is hereinafter specifically designated in the claims at the close of this specification.

My invention contemplates the simultaneous formation of a number of splints from a continuous strip or ribbon of wood cut from the log and dried. The advantage of this is that hard or inferior wood can be successfully used and rapid but thorough seasoning secured. Short strips or blanks may, however, be used in connection with my improved machine, if desired.

In carrying out my invention a blank or strip of a width and thickness equal to those of the match-splint desired to be produced is fed beneath a grating of bars arranged par-

allel with the splints when cut. A series of reciprocating knives passing between these bars simultaneously sever a number of splints. A brake or friction-clamp bears laterally on each alternate splint thus formed, while a pusher comb or rake moves in a plane parallel with the splints and shoves the alternate ones endwise a sufficient distance to allow of the proper dipping of the splints, thus forming a double comb. A continuance of this motion then shoves all the splints, or the entire comb, between clamping-bars of the splint-holder frame traversing across their line of feed, which frames travel in suitable guides to a proper receptacle. The splints are then dipped in the usual way.

The unfilling or removal of the splints from their clamping-frame, either before or after dipping, may be automatically effected by mechanism shown and described in a pending application, Serial No. 312,540, filed simultaneously herewith.

The accompanying drawings represent so much of a machine embodying all my improvements as is necessary to illustrate the subject-matter herein claimed. Some of these, however, may be used without the others and with machines differing within certain limits in the form and construction from those herein shown.

The driving-shaft side of the machine I call the "back," and the opposite or cutter side the "front." That end of the machine on the right of a person facing the front I call the "right" or "feed" end, the opposite the "left" or "discharge" end of the machine.

Figure 1 represents a top plan with the strip-roll omitted; Fig. 2, a vertical transverse section on the line 2 2 of Fig. 1, looking to the left or discharge end of the machine, as indicated by the arrow, showing more particularly the cutting and holding frame feed mechanisms; Fig. 3, a front view showing the strip-roll in dotted lines; Fig. 4, a right end elevation; Fig. 5, a left end elevation; Fig. 6, a vertical longitudinal section through the cutter-head on the line 6 6 of Fig. 5; Fig. 7, a detached plan showing the method of forming the splint-comb; Fig. 8, a perspective view of the cutter-head as seen from below; Fig. 9, a perspective of the grating between which the cutters work; Fig. 10, a vertical longitudinal section on the line 10 10 of Fig. 2, showing the friction brake or stop which acts on the splints; Fig. 11, an elevation of the inner face of one form of splint-holder frame; Fig. 12, a vertical longitudinal section therethrough on the line 12 12 of Fig. 11, and Fig. 13 a horizontal transverse section therethrough on the line 13 13 of the same figure; Fig. 14, a side or edge view showing the mode of inserting the holding-bars of the side pieces of the splint-frame; Fig. 15, a detail view on a smaller scale, being an elevation of the inner side of the holder-frame with its parts detached, to show their method of connection and disconnection more clearly.

The drawings show the entire mechanism mounted in a suitable bed-plate or main frame A. A driving-shaft B, turning in usual bearings, is driven from any suitable prime mover by well-known means—such as a fast and loose pulley B' at one end, the other end carrying a balance or fly wheel B² to equalize the motion of the various parts.

A face-cam C on the feed end of the machine drives a friction-roller c on an arm or frame C', rocking on pivots c' on the frame. The free end of this arm is slotted to receive a pivot-pin c² on the free end of a radius-bar C², pivoted on the shaft d of the feed-wheel D, and carrying a spring-pawl c³ acting on a ratchet-wheel C³, which actuates the feed-wheel, to which intermittent motion in one direction is thus imparted.

The drawings show the feed-wheel as turning in fixed bearings, with the ratchet-wheel integral with or secured to it, and with an annular groove d' in its periphery, for a purpose hereinafter explained.

Fig. 3 shows in dotted lines a reel or spool E, upon which the strip e is wound, from whence it passes under a guide-roller E', between parallel guides E² E³, longitudinally grooved on their inner faces to receive the splint-strip. (See Fig. 4.) The outer ends of these guide-bars are clamped by set-screws between holding-bars e² e³, while their inner ends are similarly held by slots and set-screws e⁴. This organization enables me to adjust the guides to strips of varying width. The inner guide-bar E², it will be seen, lies in the annular groove d', tangential to the surface of the feed-wheel, the result being that the feed-wheel D extends up between the guides and bears on the underside of the splint-strip as it is fed to the cutters. (See Fig. 4.) A pressure-roll F is mounted on a shaft f, the journals of which traverse slots f' in the frame. Springs F' bear on these journals, their pressure thereon being regulated by a set-screw F². The pressure-roller is thus held down upon the splint-strip to insure the proper bite and feed, and is free to yield to accommodate variations in the thickness of the strip, which is thus securely held on all sides while being fed to the cutters.

The splint-strip is fed over a cutter-block G until it abuts against a suitable stop g in the guideway. This block is preferably of wood or some equivalent resilient material. It is securely held in place laterally by a guide-slot in the frame and by a holding-bar G', removably secured to the frame by clamp-screws g'. A metal plate g² under the cutter-block rests on adjusting-screws G² G³, by which means the cutter-block, while rigidly supported, is rendered adjustable vertically to bring it in proper relation to the other mechanism. A grating H, Figs. 2 and 9, provided with parallel bars h transverse to the line of travel of the strip, is mounted on the frame over the cutter-block, so as to leave

room for the strip to pass under it, the strip lying between the cutter-block and grating while the splints are severed.

The cutter I is composed of a series of parallel flat endwise-adjustable blades i in a recessed cutter-head I', being held laterally therein by suitable bearing-bars i^2 i^3 and clamp-screws i^4 i^5 . Set-screws I^2 , passing through the top of the cutter-head, press these blades endwise into proper position, each cutter being separately adjustable by its own screw. The cutters lie parallel with and work through the spaces of the grating H to sever the splints. (See Fig. 6.)

15 The cutter-head I' is adjustably held in a stout frame J^2 by set-screws I^6 passing through a bearing-bar I^4 . The frame is further strengthened by a cross-bar I^5 . The cutters are thus firmly held against working strains 20 while readily removable or separable. The cutter-frame is mounted on an arm J' rocking on a pivot j' . An eccentric-link J on the driving-shaft is connected with this arm by a pivot j , to actuate the cutters. Adjustable 25 guide-stops J^3 on the frame limit lateral play of the cutter-head and keep the cutters in correct relation to the grating. A cam K on the driving-shaft vibrates a friction-roller k on an arm K' , rocking on a pivot k' , and connected at its free end by a pivot K^3 to a pitman K^3 , adjustable in length by a screw-coupling k^3 , of well-known construction. A pin l connects this pitman to a slide L, movable endwise in guides l' on the frame. The 30 front end of this slide carries a pusher-rake, consisting of a flat comb L' , the teeth l^2 of which are of a distance apart about equal to the width of the splint or to the spaces between the cutters, the depth of the teeth being about equal to the distance it is desired 35 to move the alternate splints to form the comb. The rake may be removably attached to the slide to permit of the insertion of rakes having longer or shorter teeth to move the splints the desired distance. The rake moves endwise in the plane of the splint-strip transversely to its line of traverse in order to intersect and move the splints endwise into the holder.

40 One set of splints is simultaneously severed by a single stroke of the cutters in one direction while held between the cutter-block and grating. The cutter then withdraws and the rake advances, pushing all the splints endwise until the ends of the alternate splints 45 pass under the teeth m of a brake or friction holder M, Fig. 10, which bears on the alternate splints n hard enough to hold them, while the others n' are shoved endwise far enough to form the comb N, Fig. 7. The friction-holder M, it will be seen, rests in a slot in the frame, being held against accidental displacement by springs m' , which at the same time permit it to yield slightly to accommodate 50 accidental variations in the thickness of the splints. After the comb is formed, as above described, the continued advance of

the pusher-rake shoves the entire comb endwise and inserts it between the bars of a holder-frame O. This frame may be made in 50 various ways; but the preferred construction is that shown in Figs. 11 to 15, which consists, essentially, of a frame composed of side and end pieces and intermediate bars, between which the splints are held. The end pieces 75 O' are fastened to the side pieces O² at one end, but removably connected at the other. The holding-bars O³ are likewise fastened at one end to one of the side pieces and detachably secured to the other. They may all be 80 fastened at one end or secured alternately to opposite side pieces, as shown.

The holding-bars are preferably made in the way shown in Figs. 11 to 14—that is, with elastic or yielding sides between which 85 the splints are inserted and held. The yielding surfaces are shown as composed of metal C-shaped springs O⁴, secured centrally to each alternate holding-bar, the splints thus being held by spring-pressure on one side 90 against the solid side of the adjacent bar.

An eccentric P on the driving-shaft is connected by an adjustable link P' with a crank P² on a rock-shaft P³, mounted in suitable bearings in the front of the frame above the 95 cutters. It in fact has its bearings in a guide-frame R, secured to the front of the main frame, and carries crank-arms p p, to which spring-pawls p' p' are hinged. These pawls engage with the holder-frame O, or 100 with their bars, and feed them step by step athwart the line of traverse of the combs of splints, which are successively inserted between their appropriate bars.

The holder-frames traverse in a stationary 105 flanged guideway R'. They are prevented from being pressed away from the pusher-rake by lugs r on each side of the guideway, and are in like manner prevented from passing too rapidly across the line of traverse of 110 the rake by a friction-bar R², held by screws r² and rubber springs r³, which allow it to yield slightly when required.

The filled holder-frames pass from the straight part of the guideway to and through 115 its curved end or spout R³, which discharges them into a suitable receptacle.

Having thus fully described the construction, organization, and operation of my improved machine for cutting and filling match-splints, what I claim therein as new and of my own invention is—

1. The combination, substantially as hereinbefore set forth, of a driving-shaft, an actuating-cam thereon, a rocking frame pivoted on the frame or bed-plate, an arm driven by the cam and adapted to oscillate the rocking frame, a feed-wheel mounted on the frame, a radius-bar, a pawl carried by the radius-bar, and a ratchet-wheel actuated by the pawl to 125 impart an intermittent feed in one direction to the feed-wheel.

2. The combination, substantially as hereinbefore set forth, of a reciprocating pawl, a

ratchet-wheel and feed-wheel actuated thereby, a circumferential groove in the face of the feed-wheel, and splint-strip guides, one of which lies tangentially in the groove of the feed-wheel, to enable the wheel to bear upon the strip between the guides.

3. The combination, substantially as hereinbefore set forth, of splint-strip guides having longitudinal grooves on their inner faces, in which the strip moves, a feed-wheel working between the opposite faces of the guides, a clamping or presser roll, its yielding bearings and adjusting devices to vary the pressure on the splint-strip and accommodate inequalities in thickness.

4. The combination, substantially as hereinbefore set forth, of splint-strip guides having longitudinal grooves on their inner faces, in which the strip moves, the slots in the guides, clamping mechanism, substantially such as described, to render the guides laterally adjustable to accommodate strips of varying widths, a feed-wheel, a presser-roller working between the opposite faces of the guides and mounted in open bearings, the spring bearing on the journal of the presser-roller, and the adjusting-screw for varying the tension of the spring and holding the presser-roller down to its work.

30 5. The combination, substantially as hereinbefore set forth, of a driving-shaft, an eccentric thereon, a cutter-head driven thereby, pivots on which it rocks, a cutter-block, and a grating interposed between the block and cutter, through which grating the cutters work simultaneously to sever a series of splints from a strip.

40 6. The combination, substantially as hereinbefore set forth, of an oscillating recessed cutter-head, a series of parallel cutters mounted side by side therein, and means, substantially such as described, for adjusting each cutter independently of the others.

45 7. The combination, substantially as hereinbefore set forth, of a cutter-frame, a cutter-head mounted in guides therein, cutters mounted in the head, and devices, substantially such as described, for adjusting the cutter-head in its frame and for rigidly securing it thereto at any desired elevation.

55 8. The combination, substantially as hereinbefore set forth, of cutters, a cutter-head in which they are mounted, pivots on which it rocks, a grating between the bars of which the cutters traverse to sever the splints, and adjustable guides to hold the cutter-head in correct alignment with the grating.

60 9. The combination, substantially as hereinbefore set forth, of cutters acting simultaneously to sever a series of splints, friction brakes or stops abutting against each alternate splint, and a pusher-rake which moves each alternate splint endwise the distance required to form the comb or pack.

65 10. The combination, substantially as hereinbefore set forth, of a cutting-plate, a grating between which and the cutting-plate the

splint-strip is fed, cutters traversing between the bars of the grating to sever the splints, brakes or friction-stops abutting against each alternate splint, and a pusher-rake traversing athwart the line of travel of the splints to move the alternate splints endwise the distance required to form the comb or pack.

70 11. The combination, substantially as hereinbefore set forth, of a driving-shaft, an actuating-cam thereon, a rocking arm driven thereby, a pitman connecting them, a slide movable endwise in guides, and a pusher comb or rake carried by the slide to form the splints into a comb and insert them in the holder.

75 12. The combination, substantially as hereinbefore set forth, of a pusher-rake, its slide, its pitman, and the devices for adjusting the length of the pitman to vary the traverse of the pusher-rake.

80 13. The combination, substantially as hereinbefore set forth, of a grating athwart which a splint-strip is fed, cutters reciprocating athwart said grating to sever the splints, and a pusher-rake moving transversely to the line of the feed to push the splints endwise into the clamping-frame.

85 14. The combination, substantially as hereinbefore set forth, of splint-strip-feeding mechanism, a cutting-plate and grating between which the strip passes, cutters traversing through the grating to sever the splints, friction-stops acting on alternate splints, and a pusher-rake acting first on the free strips to form a comb and then on all the splints to move them out of the path of the strip.

90 15. The combination, substantially as hereinbefore set forth, of a driving-shaft, an eccentric thereon, a pitman actuated thereby and in turn actuating a crank-arm, a vertical guide for the splint-holding frame to which the crank-arm is pivoted, a rock-shaft vibrated by the said arm, devices for adjusting the length of the pitman, a downwardly-projecting spring-pawl mounted on the rock-shaft, and a splint-holding frame traversed by the pawl.

95 16. The combination, substantially as hereinbefore set forth, of cutters simultaneously severing a series of splints from a blank or strip, a pusher traversing athwart the line of feed of the strip to move the splints endwise, and a splint-holding frame traversing athwart the line of movement of the pusher to receive the splints therefrom.

100 17. The combination, substantially as hereinbefore set forth, of a splint-holding frame, a guide in which it traverses, and a pawl acting directly on the holding-bars of the splint-holding frame between the ends thereof to give it a step-by-step movement.

105 18. The combination, substantially as hereinbefore set forth, of splint-strip-feeding mechanism, a grating across which the strip travels, cutters which sever the splints, friction brakes or stops acting on alternate strips, a pusher-rake shoving the splints endwise, a

splint-holding frame, and actuating-paws, whereby a series of splints are simultaneously cut from the strip, formed into a comb, and secured in the holding-clamp by one continuous operation.

19. The combination, substantially as hereinbefore set forth, in a splint-holding frame, of parallel bars, interposed clamping-springs, and a detachable side piece.

20. The combination, substantially as hereinbefore set forth, of the main frame having a slot or opening therein, the cutter-block fitting this opening, and its supporting and adjusting screws.

21. The combination, substantially as hereinbefore set forth, of the main frame having a slot or opening therein, the cutter-block fitting this opening, its supporting and adjusting screws, and the removable front

22. The combination, substantially as hereinbefore set forth, of the main frame having a slot or opening therein, the cutter-block fitting this opening, and its supporting and adjusting screws, and the removable front clamping-bar which ordinarily retains the block in position while permitting its removal.

22. The combination, substantially as hereinbefore set forth, of the main frame having a slot or opening therein, the cutter-block fitting this opening, and its supporting and adjusting screws, and the removable front clamping-bar which ordinarily retains the block in position while permitting its removal.

inbefore set forth, of the main frame having a slot or opening therein, the cutter-block fitting this opening, and the rigid bed or cushion between the screws and block.

23. The combination, substantially as hereinbefore set forth, of the holder-frame guideway, the holder, the friction-bar, the springs, and the adjusting-screws to control the rapidity of the movement of the holder in the guideway.

24. The guideway for the holder-frame constructed, as set forth, with a flanged vertical stationary straight portion, and an outwardly-curved bottom to change the direction of the filled holder-frame.

In testimony whereof I have hereunto subscribed my name.

McCLINTOCK YOUNG.
